We claim the ornamental design for a suction handle, as shown and described.

DESCRIPTION

FIG. 1 is a front elevational view of a suction handle in accordance with our new design;

FIG. 2 is a rear elevational view thereof;

FIG. 3 is a left side elevational view thereof;

FIG. 4 is a right side elevational view thereof;

FIG. 5 is a bottom plan view thereof;

FIG. 6 is a top plan view thereof;

FIG. 7 is a top, front, and right side perspective view thereof; and,

FIG. 8 is a bottom, front, and right side perspective view thereof.

The broken lines in the drawings illustrate portions of the suction handle that form no part of the claimed design.
